UNITED STATES PATENT OFFICE

HUGH R. CARR, OF CHICAGO, ILLINOIS

PULVERIZER MILL

Application filed February 10, 1930. Serial No. 427,304.

The object of this invention is to provide a simple roller type of mill for finely pulverizing coal, etc.

In the drawings annexed—

5 Fig. 1 is a vertical sectional view taken on the zigzag line indicated on Fig. 2;

Fig. 2 is a plan view of the roll system with the top plate removed.

Referring to the drawings annexed by reference-characters, 5 designates a vertical shaft which may be driven by any suitable mechanism from below, a part of one of the gears being shown at 6. This shaft extends up through the bottom plate 7 of the apparatus and has keyed to its upper end a pair of plates 8 and 9 spaced far enough apart to receive a series of rolls, hereinafter described. As a convenient means of spacing these plates apart, I employ a collar 10.

15 Supported in the framework 11 of the apparatus is a grinding-ring 12 which lies coincident with the space between the plates 8 and 9. The material to be comminuted is introduced into the apparatus through a spout 13 which delivers the material into the space between the disks through an annular series of openings 14 formed in the upper disk.

20 Secured to the under face of the lower disk 9 is a series of radial plow-plates 15 which work in an annular space formed above the bottom plate 7 by the frame 11. In the wall 11 is formed a series of openings or louvers 16. Supported freely between the two disks

25 and resting entirely upon the lower disk are two series of rolls, the outer series being designated by the numeral 17 and the inner series by the numeral 18. These rolls have flat peripheries and they are axleless, their sole support being the lower disk 9. These disks rest freely upon the lower roll and, therefore, when the disks are rotated through the medium of the shaft 5 they are subjected to a centrifugal action. The outer series of rolls 17

30 bear and roll against the inner face of the grinding-ring 12, while the inner series of rolls 18 have their flat peripheries in contact with the flat peripheries of the aforesaid outer rolls and are therefore rotated thereby.

35 The outer rolls are of equal weight and size,

and the inner rolls are desirably smaller in diameter but are of equal weight and size.

In operation, the rolls will have a planetary action in that they will be bodily moved around the center of the shaft by means of the lower disk, which they gravitationally engage with sufficient friction to thus bodily move them, and also rotate on their respective axes. The outer rolls are rotated on axes by engagement with the grinding-ring 12, and 40 these outer rolls in turn frictionally drive the inner rolls. By properly proportioning the inner and outer sets of rolls, it will be seen that one of the inner rolls will project partly into the space between the adjacent pair of 45 outer rolls and will remain in contact therewith during the rotation of the shaft. In this way, not only the outer set of rolls, but the inner set of rolls also will be automatically kept properly spaced with reference to each other. 50

The material fed through the upper disk 8 will first be ground between the contacting flat faces of the two sets of rolls and will then be delivered off the outer edge of the lower disk 9. The plows 15 will be so shaped as to 55

throw the powdered material up into the spaces between the outer rolls so that it will be caught between the peripheries of said rolls and the grinding-ring 12 and will be thereby further ground. By properly adjusting the feed of the material with respect to the grinding capacity of the apparatus, the material will be ground to a fine powder. During the operation of the apparatus, air is 60 drawn upwardly through the apparatus, through a cylindrical housing 19 mounted on top of the structure wall 11 and this air will be drawn in through the louvers 16 and the surrounding conduit 20. The air will pick 65

up the material ground to a sufficient fineness to be carried by air and this dust will be delivered out through the top of the housing 9 to any suitable source of collection or use. The manner in which the dust-laden air is 70 disposed of is not illustrated, as it forms no part of this invention. Neither is the conduit 20 or gearing 6 shown fully, as they form 75 no part of this invention. The gearing and the lower part of the shaft 5 will be suit-

ably housed; I show part of this housing at 21.

It is important that the outer rolls 17 shall be spaced apart in order that the plows 15 shall be capable of throwing up the partly ground material into position between the wheel 17 to be re-ground against the inner face of ring 12. It is also important that the proportions of the parts and the number of the rolls 17 shall be such that when all the rolls are acted on by centrifugal force to an equal extent (which of course will be the case, since they are all supported freely between the discs 8 and 9) the inner set of rolls 18 shall be prevented from being thrown out against the ring 12 and instead shall be pressed against the adjacent surfaces of the rolls 17 so as to have grinding contact therewith and be rotated thereby. It is also important that the discs 8 and 9, and particularly the lower disc 9, shall have their outer edges terminate short of the ring 12 so that there shall be provided an annular space up into which the plows may throw the partly ground material in the manner above set forth.

I have illustrated, and I prefer to use, rolling elements having flat peripheries in rolling contact, as that form of rolling element is the most efficient in reducing the material to dust form, but it will be understood that my invention is not restricted to this form of rolling element, as other forms such as oval or spherical may be used with advantage for some purposes.

What I claim as new is:

1. In a pulverizing apparatus, a frame carrying a grinding-ring facing inwardly and having means for providing a supply of air thereunder, a rotatable shaft centrally arranged with respect to said ring and carrying a pair of separated disks rotatable with the shaft, means for feeding material through the upper disk, and a system of grinding elements arranged between the disks embodying an outer set of rolls having flat peripheries working against the face of the aforesaid grinding-ring and an inner set of rolls having their flat peripheries rolling against the peripheries of the aforesaid outer set of rolls, all of these rolls being supported freely on the lower disk so as to have not only a body rotation but also an axial rotation.

2. In a pulverizing apparatus, a frame carrying a grinding-ring facing inwardly, a rotatable shaft centrally arranged with respect to said ring and carrying a pair of separated disks, rotatable with the shaft, means for feeding material into the space between the disks, and a system of rolling grinding elements arranged between the disks embodying an outer set of rolling elements having rolling contact against the face of the aforesaid grinding-ring and an inner set of rolling elements having rolling contact against the peripheries of the aforesaid outer set of rolling elements, all these elements being supported freely on said lower disk so as to have not only a body rotation but also an axial rotation and be held in rolling contact by centrifugal force, the lower one of said disks terminating short of the grinding ring and rotating means being provided below said lower disk to throw back

er set of rolling elements, all these elements being supported freely on said lower disk so as to have not only a body rotation but also an axial rotation and be held in rolling contact by centrifugal force.

3. In a pulverizing apparatus, a frame carrying a grinding-ring facing inwardly, a rotatable shaft centrally arranged with respect to said ring and carrying a pair of separated disks rotatable with the shaft, means for feeding material into the space between the disks, and a system of grinding elements arranged between the disks embodying an outer set of rolls having flat peripheries working against the face of the aforesaid grinding-ring and an inner set of rolls having their flat peripheries roll against the peripheries of the aforesaid outer set of rolls, all of these rolls being supported freely on the lower disk so as to have not only a body rotation but also an axial rotation and be held in place by centrifugal force.

4. In a pulverizing apparatus, a frame carrying a grinding-ring facing inwardly, a rotatable shaft centrally arranged with respect to said ring and carrying a pair of separated disks, means for feeding material into the space between the disks, and a system of rolling grinding elements arranged between the disks embodying an outer set of rolling elements having rolling contact against the face of the aforesaid grinding-ring and an inner set of rolling elements having rolling contact against the peripheries of the aforesaid outer set of rolling elements, all these elements being supported freely on said lower disk so as to have not only a body rotation but also an axial rotation and be held in rolling contact by centrifugal force, said outer set of rolling elements being separated and rotating means being provided below the spaces between the rolling elements for throwing upwardly the material for re-grinding against the aforesaid grinding-ring.

5. In a pulverizing apparatus, a frame carrying a grinding-ring facing inwardly, a rotatable shaft centrally arranged with respect to said ring and carrying a pair of separated disks, means for feeding material into the space between the disks, and a system of rolling grinding elements arranged between the disks embodying an outer set of rolling elements having rolling contact against the face of the aforesaid grinding-ring and an inner set of rolling elements having rolling contact against the peripheries of the aforesaid outer set of rolling elements, all these elements being supported freely on said lower disk so as to have not only a body rotation but also an axial rotation and be held in rolling contact by centrifugal force, the lower one of said disks terminating short of the grinding ring and rotating means being provided below said lower disk to throw back

the material for re-grinding against the face of said grinding-ring.

6. In a pulverizing apparatus, a frame carrying a grinding-ring facing inwardly, a rotatable shaft centrally arranged with respect to said ring and carrying a pair of separated disks, means for feeding material into the space between the disks, and a system of rolling grinding elements arranged between the disks embodying an outer set of rolling elements having rolling contact against the face of the aforesaid grinding-ring and an inner set of rolling elements having rolling contact against the peripheries of the aforesaid outer set of rolling elements, all these elements being supported freely on said lower disk so as to have not only a body rotation but also an axial rotation and be held in rolling contact by centrifugal force, the spaces between the outer series of rolling elements being insufficient to permit the inner rolling elements to pass outwardly by centrifugal force into the spaces between the outer series of rolling elements, whereby the spaces between the outer rolling elements will be maintained and all the rolling elements will have their positions maintained by centrifugal force alone, means being provided below the lower disk for continuously throwing the partly ground material upwardly into spaces between the outer rolling elements to be re-ground against the grinding-ring.

In testimony whereof I hereunto affix my signature.

HUGH R. CARR.
